FOREIGN PATENT DOCUMENTS

CN 302972198 10/2014

Primary Examiner — David G Muller
Assistant Examiner — Nathan M Johnston(57) **CLAIM**

The ornamental design for a product dispenser, as shown and described.

DESCRIPTION

FIG. 1 is a front elevation view showing my new design for a product dispenser;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is a front, right side perspective view thereof.

The broken lines shown in the drawings are included for the purpose of illustrating portions of the product dispenser and form no part of the claimed design.

1 Claim, 4 Drawing Sheets(56)
